UNITED STATES PATENT OFFICE.

ALEXANDER M. GRAY, OF MILWAUKEE, WISCONSIN, ASSIGNOR, BY MESNE ASSIGNMENTS, TO ALLIS-CHALMERS MANUFACTURING COMPANY, A CORPORATION OF DELAWARE.

DYNAMO-ELECTRIC MACHINE.

1,086,818.

Specification of Letters Patent.

Patented Feb. 10, 1914.

Application filed October 27, 1910. Serial No. 589,439.

To all whom it may concern:

Be it known that I, ALEXANDER M. GRAY, a subject of the King of England, residing at Milwaukee, in the county of Milwaukee and State of Wisconsin, have invented certain new and useful Improvements in Dynamo-Electric Machines, of which the following is a full, clear, and exact specification.

10 This invention relates to dynamo-electric machines, and more particularly to means whereby such machines can be kept in a cool and economical operating condition.

In order to keep the temperature of dynamo-electric machines within certain prescribed limits, it is customary to provide them with some means of ventilating, such as a fan blade construction by means of which a forced circulation or flow of air is created. It is found that the currents of air which are drawn into a machine have a great tendency to eddy and circle around the various parts, especially if these parts extend or lie in the paths of the cooling currents. Great attention is given to the cooling of windings, in which a considerable degree of heat is developed. In order to convey away heat thus developed, cooling fluid currents are directed on the windings of dynamo-electric machines, but, due to the fact that these currents of fluid eddy they become heated quite excessively after circling around a coil or winding a very few times.

35 It is the object of this invention to provide simple and inexpensive means whereby this eddying or circling of cooling currents will be overcome so that the cooling fluid will come in contact only once with the operating structure or parts to be cooled and then pass out of the machine.

This invention is illustrated on the accompanying sheet of drawings in which—

Figure 1 is a longitudinal elevation, partly in section, of an induction motor equipped with my invention; and Fig. 2 is a fragmentary end elevation, made on a smaller scale, of that shown in Fig. 1.

I do not intend to limit my invention as applied to induction motors but intend to use it in connection with all different types of dynamo-electric machines.

The various novel features of my invention will be described in the specification

and particularly set forth in the appended claims.

Mounted upon the shaft 10 of the induction motor illustrated is a spider 11 comprising mainly a hub 12 and radial arms 13 which support an integrally formed rim 14. This rim includes an annular portion 15 against which a laminated core 16 is forced when mounted upon the rim 14. The laminated core is held between the annular portion 15 and an end plate 17, which is retained in position by a split ring 18 adapted to be secured in a slot in the rim 14. The core 16 is provided with a winding 19 including conductors which project beyond the core and are secured to short-circuiting rings 20, which are provided with integrally formed fan blades 21. The shaft 10 rotates in bearings which are mounted in the bearing housings 22 formed integrally with the end housings 23. The end housings are secured to the yoke 24 of this machine by bolts 25. Secured in the usual way in the yoke of the machine is a stationary laminated core 26, which is provided with a winding 27 having end turns projecting beyond the core.

When the machine is set in operation currents of air are drawn in through openings 29 in the end housings 23 by the action of the fans 21. The air, after being drawn in, is further forced into intimate contact with the projecting end portions of the rotor and stator conductor windings to convey away the heat developed in said windings. Reiterating, there is a great tendency for these currents of cooling air, after having once passed the fans and end portions of the rotor and stator windings, to again circle around and traverse precisely the same paths which they have previously traversed within the machine. This time, however, the air naturally is somewhat more heated and its capacity for absorbing heat from the windings is materially decreased and limited. It is seen readily that if these same currents of air only circulate around the rotor and stator windings a comparatively few times the air will become extremely warm, the heat developed in the windings of the machine will cease to be absorbed by the circulating currents and the machine will heat up more and more, making its operation dangerous, less economical than de-

sirable and possibly render the machine useless. In order to prevent this continual eddying or circling of air currents around the fans and windings of a machine after 5 the air has been drawn in by the fans, means has been provided for directing these currents of air out of the machine in a direction parallel to or away from the axis of the machine after the cooling air has once 10 passed the windings and absorbed heat developed therein. When the discharged air is thus directed there is little likelihood of its being immediately recirculated through the fans. This means comprises annular 15 baffles 30 in the form of open ended cones which are secured to the end housings 23 in any suitable manner, such as by rivets 31. These cone-shaped baffles may, however, be 20 removably secured in position and may be located in any convenient place or places within the housing as long as they intercept the paths of the cooling currents which tend to eddy.

As here shown the baffles are secured to 25 the end housings adjacent to the end portions of the windings so that the baffles divide the opening formed in said end housing into inner and outer parts. The air is drawn in through the inner part and 30 forced out through the outer part of the end housings after having absorbed heat from the windings. The baffles or deflectors, which extend substantially longitudinally 35 of the machine, as stated before are cone-shaped or somewhat funnel-shaped so that there is a nozzle action, the velocity of the air being increased upon entering. The air used for cooling, in addition to being driven out over the baffles, may escape through the 40 opening 32 formed in the stator yoke. By means of this arrangement a maximum amount of heat is absorbed by the ventilating currents and conveyed away, maintaining the machine in a safe, cool, and economi- 45 cal operating condition.

What I claim as new is:

1. In a dynamo-electric machine, means for causing circulation of a cooling fluid

through a portion of said machine, an end member provided with openings, and a cooling fluid guiding end member attached to the inner side of said member to insure the ingress and discharge of fluid through different portions of said openings. 50

2. In a dynamo-electric machine, the combination of rotor and stator windings, an end member provided with ventilating openings, means for drawing cooling fluid through a portion of said end member and past portions of said windings, and a cooling fluid guiding member for preventing the re-circulation of fluid within said end member and insuring the discharge of said fluid adjacent to said guiding member and in a direction away from the windings. 60

3. In a dynamo-electric machine, the combination of rotary and stationary windings having projecting end portions, a ventilating end member surrounding said end portions, means for drawing in a cooling fluid 70 through one portion of said end member past the end portions of said windings, and means engaging said end member for deflecting said fluid flow from an eddying path and out through another portion of said end 75 member.

4. In a dynamo-electric machine, the combination of rotor and stator windings, an end member provided with a ventilating opening, means for causing the circulation 80 of cooling fluid through said end member and past portions of said windings, and fluid guiding means for insuring the discharge of said fluid adjacent to said guiding member, and in a direction parallel to or 85 away from the axis of said machine, whereby the circulation of heated fluid in the immediate vicinity of the machine is prevented.

Milwaukee, Wis., Oct. 12, 1910.

In testimony whereof I affix my signature, in the presence of two witnesses.

ALEXANDER M. GRAY.
